US00D782557S

(12) **United States Design Patent** (10) **Patent No.:** **US D782,557 S**
(45) **Date of Patent:** **** Mar. 28, 2017**

(54) **MONITORING CAMERA**

(71) Applicant: **AXIS AB**, Lund (SE)

(72) Inventors: **Daniel Ahman**, Lomma (SE); **Henrik Svedberg**, Loddeko pinge (SE); **Christian Jacobsson**, Lund (SE); **Mikael Persson**, Malmo (SE); **Kent Fransson**, Malmo (SE); **Samir Helaoui**, Malmo (SE); **Mathias Walter**, Arlov (SE); **Morten Bergstrom**, Bjarred (SE)

(73) Assignee: **AXIS AB**, Lund (SE)

(**) Term: **15 Years**

(21) Appl. No.: **29/545,550**

(22) Filed: **Nov. 13, 2015**

(57) **CLAIM**

The ornamental design for a monitoring camera, as shown and described.

DESCRIPTION

FIG. 1 is a perspective view of a first embodiment of a monitoring camera showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom plan view thereof; and

FIG. 7 is a top plan view thereof;

FIG. 8 is a perspective view of a second embodiment of a monitoring camera showing our new design;

FIG. 9 is a front elevational view thereof;

FIG. 10 is a left side elevational view thereof;

FIG. 11 is a right side elevational view thereof;

FIG. 12 is a rear elevational view thereof;

FIG. 13 is a bottom plan view thereof; and,

FIG. 14 is a top plan view thereof.

The broken lines depict portions of a monitoring camera in which the design is embodied and form no part of the claimed design.

The parts shown with broken lines are not considered to be a part of the claimed design.

1 Claim, 12 Drawing Sheets
